UNITED STATES PATENT OFFICE.

ETHAN I. DODDS, OF PITTSBURGH, PENNSYLVANIA, ASSIGNOR TO FLANNERY BOLT COMPANY, OF PITTSBURGH, PENNSYLVANIA.

RAIL-JOINT.

1,250,149.

Specification of Letters Patent. Patented Dec. 18, 1917.

Application filed May 15, 1916. Serial No. 97,689.

To all whom it may concern:

Be it known that I, ETHAN I. DODDS, a citizen of the United States, and a resident of Pittsburgh, in the county of Allegheny and State of Pennsylvania, have invented certain new and useful Improvements in Rail-Joints; and I do hereby declare the following to be a full, clear, and exact description of the invention, such as will enable others skilled in the art to which it appertains to make and use the same.

This invention relates to improvements in rail joints,—one object of the invention being to so construct a rail joint that it may be placed between the ties and rail and have sufficient strength to insure maximum carrying capacity.

A further object is to provide a rail joint or chair which may be used with rails having their sections connected by splice bars or fish plates as now in use, and serve to reinforce or supplement such splice bar or fish plate constructions.

A further object is to so construct a rail joint chair as to provide a transverse bolster which shall also serve as a seat for the meeting ends of two rail sections.

With these and other objects in view, the invention consists in certain novel features of construction and combinations of parts as hereinafter set forth and pointed out in the claims.

In the accompanying drawings; Figure 1 is a perspective view of a rail joint showing one embodiment of my invention; Fig. 2 is a transverse sectional view; Fig. 3 is a longitudinal sectional view; Fig. 4 is a transverse section showing a rail in position; Fig. 5 is a perspective view of a rail joint showing a modified construction; Fig. 6 is an end view of the same; Fig. 7 is a transverse section; Fig. 8 a longitudinal section, and Fig. 9 a side elevation of the form of the invention illustrated in Fig. 5; Fig. 10 is a side view and Fig. 11 is a perspective view, of another embodiment of my invention; Fig. 12 is an end view and Fig. 13 is a longitudinal section of the construction shown in Figs. 11 and 12; Fig. 14 is a transverse section of the

50 same structure, showing a rail and fish plates in position; Fig. 15 is a side elevation of a further modification wherein a separate bolster is used; Fig. 15^a is a perspective view of the separate bolster; Fig. 16 is a plan view 55 of the structure shown in Fig. 15, and Fig.

17 is a transverse section; Fig. 17^a is a side elevation and Fig. 18 a plan view of another embodiment of my invention; Fig. 19 is an end view; Fig. 20 a transverse section and Fig. 21 a longitudinal section of the structure shown in Figs. 17^a and 18; Fig. 22 is a side elevation, and Figs. 23, 24 and 25 are sectional views illustrating another embodiment of the invention; and Figs. 26 and 27 are views illustrating other modifications.

My improved rail joint chair comprises, in the embodiment of the invention shown in Fig. 1 of the drawings, a plate 1 which may be made of malleable iron or steel, and the chair may be made of metal capable of being pressed into shape with the use of dies. The intermediate portion 2 of the plate 1 is depressed somewhat below the horizontal plane of the end portions 3, as clearly shown in Fig. 3. The end portions 3 of the plate 75 are adapted to rest upon the ties and are provided with spurs 4 to engage the latter,—said end portions being preferably also made with holes 5 for the accommodation of spikes. The depressed intermediate portion 2 of the 80 plate will span the space between ties and is provided centrally with a thickened portion forming a transverse bolster 6, the latter also serving to receive and provide a bearing for the meeting ends of two rail sections. At 85 respective sides of the intermediate portion two of the plate, upwardly projecting strengthening webs 7 are provided. These webs may have convex upper edges extending from end to end of the intermediate portion 2 of the plate, and said webs are provided with lateral flanges 8 projecting from their convex edges. The flanged webs constitute compression members to sustain the load brought to bear upon the bolster 6.

My improved joint chair will effectually sustain the strain brought to bear upon the meeting ends of rail sections when the joint comes between the ties and will operate to reduce to a minimum, the "hammering" 90 of the rails at the joint,—efficient trussed bolsters, such as indicated at 6—7—8, being provided to receive and sustain the meeting ends of the rail sections.

In the form of the invention shown in 105 Figs. 5 to 9, the curved webs project downwardly as indicated at 9 and provided at their lower curved edges with flanges 10. The flanged truss thus formed constitutes a tension member, instead of a compression 110

member as shown in Fig. 1, to sustain the strain which will come upon the bolster 6. In this construction, the connection between the bolster 6 and webs 9 may be further 5 strengthened by means of ribs 11.

In the construction shown in Figs. 10 to 14, the central portion of the plate is removed as indicated at 2^a and at respective sides of this open central portion, vertical 10 webs 12 are formed so as to project above and below the horizontal plane of the plate,—said webs being provided at their free upper and lower edges with lateral flanges 13—14. A bolster 15, which may be 15 made in the form of an I-beam, extends across the central space 2^a, from one web 12 to the other and is supported by said webs. In Fig. 14 of the drawings, I have shown the bolster integral with the webs and the 20 bolster 15 is so proportioned that its upper face shall be in line with the upper faces of the portions 3 of the plate and constitutes a seat for the meeting ends of the rail sections. If desired, holes 16 may be made in the portions 3 of the plate to reduce the weight of the latter. The plate or chair in this form 25 of the invention, may be provided with spurs 4 and spike holes 5, as in the constructions previously described.

30 In the embodiment of the invention shown in Figs. 15 to 17 the rail joint chair comprises three parts,—viz. two truss members and a bolster. Each truss member comprises two plates 17—17 connected by a web 18 extending above and below the plane of the plates,—said web being provided at its free upper and lower edges with lateral flanges 19, 20. The truss members are suitably spaced apart on the ties, and connected by 35 a transverse bolster 21 which, in this case, is made separate from the truss members and passed through holes 22 in the webs 18. The bolster 21 may be made in the form of an I-beam having its bottom portion curved 40 or bowed downwardly, and provided at respective ends with transverse ribs 23 which serve to prevent displacement or spreading 45 of the truss members.

In the construction shown in Figs. 17^a to 50 21, the intermediate portion of the plate or chair is cut away as indicated at 2^b, and webs 24 are formed at respective sides of said central open portion. These webs are provided at their upper edges only with 55 lateral flanges 25, and the bolster 26 is, in this construction, made integral at its ends with the webs 24. Openings 27 may be made in the plate or chair to reduce the weight of the same.

60 Figs. 22, 23, 24 and 25 show splice bars 28 which may be of cast metal having webs 29 to depend between the ties and provided at their lower edges with lateral flanges 30 which may project outwardly or said flanges 65 may project inwardly as well as outwardly.

The webs 29 may be provided with holes 32 to accommodate a bolster 33, which latter may be the same in construction as that shown in Fig. 15^a.

In the construction shown in Figs. 26 and 70 27, the intermediate portions of the respective truss members have a cross section resembling that of an I-beam. The webs 34 project above and below the plane of the end portions of the chair,—the upper edge 75 of each web being made straight and provided with lateral flanges 35, 35 projecting in opposite directions, and the lower edge of each web 34 being made curved and provided with flanges 36, 36 projecting in opposite directions. The webs 34 are provided with openings 37 to receive the ends of a bolster 38, the construction of the latter being the same as that shown in Figs. 15^a and 24.

75 Other changes might be made in the details of construction of my invention without departing from the spirit thereof or limiting its scope and hence I do not wish to restrict myself to the precise details here- 80 in set forth.

Having fully described my invention what I claim as new and desire to secure by Letters-Patent, is:—

1. A rail joint chair comprising two parallel vertically disposed webs having lateral flanges at their free edges and constituting truss members, and a transverse bolster extending from one truss member to the other and sustained by said truss members, said transverse bolster constituting a member of the chair and adapted to receive the meeting ends of rail sections. 95

2. A rail joint chair comprising flat end portions constituting seats for rail sections, 100 flanged trusses connecting said flat end portions, and a transverse bolster sustained by said trusses, the body of said bolster disposed below the plane of the upper faces of said flat end portions and having its upper face in the same plane as that of the flat end portions. 105

3. A rail joint chair, comprising a plate having a depressed central portion, said plate having trusses at the side edges of said 110 depressed portion, and a transverse bolster in said depressed portion and extending from one truss to the other and sustained thereby. 115

4. A rail joint chair provided intermediate of its ends with vertical webs at its side edges, said webs having lateral flanges at their free edges, and a transverse bolster connecting said webs, said transverse bolster constituting a part of the chair and 120 being located centrally between the ends thereof in position to receive the meeting ends of rails. 125

5. A rail joint chair comprising a plate having a depressed central portion, a trans- 130

verse bolster between the ends of said depressed portion, and webs at the side edges of said depressed portion of the plate and rigid with the ends of said transverse bolster.

6. A rail joint chair comprising a plate having a depressed central portion, upwardly projecting webs at the side edges of said depressed portion and having lateral flanges at their free edges, and a bolster

formed integral with the intermediate depressed portion of the plate and connecting said upwardly projecting webs.

In testimony whereof, I have signed this specification in the presence of two subscribing witnesses.

ETHAN I. DODDS.
